[57] CLAIM

The ornamental design for a puppet or similar article, substantially as shown and described.

DESCRIPTION

FIG. 1 is a perspective view from the upper front side of a puppet or similar article, showing my new design thereof;

FIG. 2 is a front elevational view thereof, showing the face of the design of FIG. 1;

FIG. 3 is a side elevational view thereof; the other side
being the mirror image of the side shown;

FIG. 4 is a top plan view thereof; and

FIG. 5 is a bottom plan view thereof.

FIG. 1

FIG. 5
